UNITED STATES PATENT OFFICE.

ANDREW T. RICHARDSON, OF VERONA, PENNSYLVANIA, ASSIGNOR TO VERONA TOOL WORKS, A CORPORATION OF PENNSYLVANIA.

COILING-MACHINE.

No. 861,608.

Specification of Letters Patent.

Patented July 30, 1907.

Application filed July 12, 1906. Serial No. 325,778.

To all whom it may concern:

Be it known that I, ANDREW T. RICHARDSON, a citizen of the United States, residing at Verona, in the county of Allegheny and State of Pennsylvania, have 5 invented certain new and useful Improvements in Coiling-Machines, of which the following is a specification.

My invention relates to machines for coiling rods, wire or other blanks into helical forms and has for its 10 object to produce such helices more rapidly and in more perfect form than they are now made by the machines in use.

My improved coiling machine is more particularly adapted to the making of helices from quadrilateral 15 rods or blanks, preferably while hot, which helices are specially designed for subsequent cutting up into single coils to produce the well known split washer type of nut locks. To produce high grade nut locks of this type it is most important that these helices be 20 coiled the exact size required, that they be free from irregularities, and that they have a uniform pitch or spacing between successive coils, and that there shall be no distortion of the blank while being coiled.

My machine is also adapted to the coiling of helical 25 springs and to other similar purposes.

I accomplish all these objects by feeding the blank obliquely onto the mandrel at the predetermined pitch which is to be given to the coils, whereas the usual custom is to feed the blank in at right angles to 30 the mandrel. My improved method of feeding, I have found, obviates the necessity for any grooves on the forming rolls, or for any other spacing device, either on the forming rolls, on the mandrel, or separate from either, to give the required pitch or spacing to 35 the coils of the helix. By means of this oblique feeding of the blank I am enabled to turn out the highest grade of product from a machine having its operating and wearing parts of most simple and inexpensive construction as will be seen from the following de-

40 scription.

In the accompanying drawings which form part of this specification: Figure 1 shows an elevation view of my improved coiling machine, partly in section. Fig. 2 is a view of the operating parts, the driving 45 means being eliminated, and shows a convenient guiding means for the oblique feed. Fig. 3 shows in elevation the forming rolls and their functional relation to the blank. Fig. 4 is a side view of the same rolls shown in Fig. 3.

50 Referring again to the drawings: A shaft 1 driven by suitable means, as the pulley 2-2, is mounted in the bearings 3-3 attached to the bed B, and has the gears 4 and 5 fixed thereon. A hollow shaft 6 is mounted in the bearings 7-7 and has the gear 8 fixed thereon

meshing with and rotated by the gear 4. A mandrel 9 55 of indefinite length projects from the hollow shaft 6 and is made rigid therewith by a set screw 10. The projecting end of the mandrel passes through a removable bushing 11 which is adapted to fit the particular diameter of mandrel in use and serves as a bearing 60 therefor and may be provided with a bevel at its outer end to accommodate the obliquely fed blank A. The block 12 has the slotted guide way 14 and an adjusting device which is shown simply in the drawings by means of a movable strip 15 having a slot 16 and a set 65 screw 17. Set screws 18 retain the bushing 11 in position. A head 19 rigidly connected with the gear 20 by the hollow shaft 21 is mounted in the bearing 22 and is rotated by said gear 20 meshing with the gear 5. Forming rolls 23 are attached by suitable pins 24 to 70 their adjusting blocks 25 dove-tailed in the head 19 and adjusted by the set screws 26 and washers 27; suitable set screws 28 retain the axle pins 24.

My improved machine is suitable for coiling all kinds of blanks, wire and the like, but I will describe its operation as particularly applied to the making of helices used in the production of the split washer type of nut-locks, as follows:

The blank A is fed, preferably hot and direct from the heating furnace, into the guide way 14 and onto the 80 mandrel 9, the proper size of mandrel having been inserted and the adjusting strip 15 having been set for the predetermined pitch of the helix to be formed. The blank will therefore be guided out over the revolving mandrel and along side the bevel on the bushing 11, 85 being held against said bevel by the edge of the slotted guide way 14. The head 19 revolves at a higher rate than the mandrel and in the same direction; the forming rolls engage the end of the blank and bend it down and around the mandrel and as the blank is formed into 90 the successive coils of the helix it passes into the hollow shaft 21. In the practice of making these helices for subsequent cutting up into nut-locks it is important that the freshly formed and still red hot helices be not distorted; to this end the tubular receptacle formed by the hollow shaft may be extended to a suitable length to accommodate the full length of finished helix, and it is apparent that as the hollow shaft revolves in the same direction as the entering helix, the friction on said incoming helix is reduced to a minimum, thus reducing 100 the chances of distortion thereof. The helices as formed pass on out of the hollow shaft to suitable receiving means.

The mandrel 9 is of uniform section throughout and projects from the bushing 11 sufficiently to receive a 105 few coils of the blank and as it becomes worn, may be cut off and extended out at will.

Having thus described my invention I claim as new

and desire to protect by Letters Patent of the United States:

1. In a machine for coiling helices from quadrilateral bars, the combination of a revolving mandrel, a plurality of forming rolls of uniform diameter revolving concentric to said mandrel, means for feeding a blank obliquely onto the mandrel without distortion, and means for adjusting the feeding angle of said blank, substantially as described.
2. In a machine for coiling helices from quadrilateral blanks, the combination of a revolving mandrel, a beveled bushing on said mandrel, a plurality of forming rolls hav-

ing their faces parallel with said mandrel and revolving on a head concentric to said mandrel, a slotted guide way for feeding the blank obliquely to the mandrel without distortion, and means for adjusting the feeding angle of said blank, substantially as and for the purposes set forth.

In testimony whereof I have affixed my signature in presence of two witnesses.

ANDREW T. RICHARDSON.
